(57) **CLAIM**

The ornamental design for a laptop sleeve, substantially as shown and described.

DESCRIPTION

FIG. 1 is a front perspective view of the laptop sleeve.

FIG. 2 is a front view of the laptop sleeve.

FIG. 3 is a rear view of the laptop sleeve.

FIG. 4 is a left view of the laptop sleeve.

FIG. 5 is a right view of the laptop sleeve.

FIG. 6 is a top view of the laptop sleeve; and,

FIG. 7 is a bottom view of the laptop sleeve.

The broken lines represent stitching which forms no part of the claimed design.
